UNITED STATES PATENT OFFICE.

EDMOND H. BELBER, OF PHILADELPHIA, PENNSYLVANIA.

AUTOMOBILE HORN.

Application filed April 8, 1925. Serial No. 21,534.

The object of my invention is to provide a structure, comprising automobile horn and supporting means therefor, which may be applied to any make or style of car and which is adapted to occupy a minimum of space. It is especially intended for embodiment in an automobile horn which is operated purely pneumatically by the manual compression of a bulb on the end of the horn, which bulb must, of necessity, be within convenient reach of the driver.

A preferred embodiment of the invention is shown on the accompanying drawings, in which—

Fig. 1 is a plan view of the horn and its supporting means.

Fig. 2 is a front view of the same on a reduced scale.

Fig. 3 is an enlarged section through a portion of Fig. 1 on line 3.

The horn shown is one having a plurality of sound amplifiers; that is, it is virtually a multiple horn. The invention is especially applicable to such horns, by reason of their considerable over-all length and the difficulty or impossibility, in certain types of cars, of mounting them so that they extend directly forward without overlapping the engine cover. The invention, however, is applicable to single horns as well as to multiple horns.

Embracing two units of the multiple horn *a* is a saddle *b* from which extends a post *c* having a surrounding flange *d*. Sleeved on the post *c* is an internally threaded nut *e* having at one end an internal flange extending back of the flanged part *d* of the post. A plate *g* is provided with an integral exteriorly threaded ring *f* adapted to slip over the outer end of post *c* and to be screwed into engagement with nut *e*.

Plate *g* is provided near its opposite ends with holes through which may be inserted screws or bolts for fastening the plate to a support. This support is preferably that part of the frame *x* which extends under the windshield.

The plate is so secured that the main body of the horn extends horizontally, and transversely of the car, that is, parallel to the direction of longitudinal extension of the windshield.

Back of the main body of the horn is a contracted neck *h* exteriorly threaded and adapted to be engaged by one threaded end of an arcuate tube *i*. The other threaded

end of tube *i* is threaded on one end of a straight threaded tube *k* whose other end is expanded and carries the hand operable bulb *o*. The threaded end of tube *i* carries nuts *m*, *m* and washers *n*, *n*. The threaded end of tube *i* extends through a hole that is formed in frame *x* to receive it. One nut *m* and washer *n* is on the outside of the frame and the other nut *m* and washer *n* is on the inside of the frame, and by means of the nuts, the washers are clamped against opposite sides of the frame. Thereby the horn is provided with an auxiliary support that relieves the strain on plate *g*.

The horn may be so positioned that the bulb is convenient to the left hand of the driver, or it may extend in the reverse direction so that the bulb will be convenient to the right of the driver.

The tubular part *h* of the horn may extend horizontally as shown; or the arcuate tubular joint *i* may be turned on the main body of the horn as a pivot so that the bulb end of the horn may be positioned either above or below the level of the pivot. Therefore, in attaching the horn to the car, the bulb *o* may be located at any desired level within a reasonable range, and at any desired lateral position.

Having now fully described my invention, what I claim and desire to protect by Letters Patent is:

1. An automobile horn structure comprising a supporting frame, a horn comprising a main member including the sound amplifier, a rear member comprising a tube, an arcuate tubular joint uniting the tube and the main member, and horn supporting means carried on the outside of the frame and engaging the main member of the horn, said main member extending laterally along the outside of the frame, and said tube extending through and supported by the frame and extending in angular relation to the main member and the frame.

2. An automobile horn structure comprising a supporting frame, a front horn member comprising a sound amplifier extending in front of the frame, a rear horn member comprising a sound conveying tube extending through the frame in angular relation to the front horn member, a connecting tubular member between the front and rear members of the horn, and means to independently support the front and rear members of the horn from the frame.

3. An automobile horn structure comprising a laterally extending supporting frame, a horn comprising a main member including the sound amplifier extending in front of and substantially parallel to the support, a threaded ring, means by which the threaded ring is carried by the supporting frame, a saddle supporting the amplifier, a post on

the saddle, the outer end of the post extending within said ring, and a nut sleeved on ¹⁰ the post and engaging said threaded ring.

In testimony of which invention, I have hereunto set my hand, at Philadelphia, Pennsylvania, on this 7th day of April, 1925.

EDMOND H. BELBER.
